UNITED STATES PATENT OFFICE.

HENRIK AUGUST BERTHEAU, OF STOCKHOLM, SWEDEN.

VALVE-GEAR FOR EXPLOSIVE-ENGINES.

SPECIFICATION forming part of Letters Patent No. 660,242, dated October 23, 1900.

Application filed January 14, 1898. Serial No. 666,730. (No model.)

To all whom it may concern:

Be it known that I, HENRIK AUGUST BERTHEAU, engineer, a subject of the King of Sweden and Norway, residing at Stockholm, Sweden, have invented certain new and useful Improvements in Gas or Petroleum Engines; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 This invention has relation to hydrocarbon and similar motive-fluid motors, and more particularly to means for starting the same whereby the operation of the motor can be changed from a two-cycle to a four-cycle motor, and vice versa.

It has heretofore been the practice to use a fluid under pressure for starting hydrocarbon or like motive-fluid motors, the starting fluid being stored in a receiver, so that at 25 each starting the receiver has to be charged by means of a pump, compressed air being the fluid generally used.

One of the objects of my invention lies in the provision of means whereby after a first 30 charging of the receiver for the starting fluid said receiver is kept charged by the motor, in that products of combustion or waste gases, instead of being exhausted into the atmosphere, are in part forced into said receiver until the pressure therein is substantially equal to the explosive force of a charge 35 of combustible vapor or gas, a pressure which is sufficient to start the motor.

40 A further object of my invention lies in the provision of means whereby the operation of the motor may be changed from a two-cycle to a four-cycle motor, and vice versa.

That my invention may be fully understood I will describe the same in detail, reference being had to the accompanying drawings, in which—

Figure 1 is a sectional fragmentary elevation, and Fig. 2 a top plan view, of so much of a vertical hydrocarbon-motor as will be 50 necessary to a full understanding of my improvements.

In the figures of the drawings, A indicates

the power-cylinder, a the exhaust-valve, and b' the inlet-pipe for the explosive compound connected with the vaporizer, (shown in dotted lines in Fig. 1 as contained in a cylinder B,) b² being the loaded inlet-valve for said vaporizer, the movements of which valve are limited by a collar b on the valve-stem moving between suitable abutments, the load—i. e., 60 the stress of the spring acting on the valve b²—being so regulated as that said valve will open as soon as the pressure in the vaporizer is lower than the atmospheric pressure.

The parts described are of well-known construction and arrangement, except that the stem a' of the exhaust-valve a projects some distance above the upper cylinder-head for purposes presently explained.

The explosive-chamber or upper end of the power-cylinder is in communication with one of the branches of a valve-casing C', whose other branch is connected by a pipe C with a storage vessel C² for the starting fluid, the valve c in said casing C' opening outwardly 75 or from the power-cylinder and held to its seat by a spring c', the branch pipe C, leading to the storage vessel C², being provided with a suitable cut-off valve manipulated by a hand-wheel c² or otherwise. The stem a' 80 of the exhaust-valve a has secured thereto a flanged sleeve a², straddled by the forked end of a lever f, fulcrumed about midway of its length to a fixed part of the motor.

To the upper head of the power-cylinder A 85 are secured two bearings k' for a valve-controlling rod k, and in suitable bearings p' is fulcrumed a bell-crank lever p, whose vertical arm is held in contact with the proximate end of rod k by a spring p². The horizontal 90 arm of the bell-crank lever p is forked and straddles a flanged sleeve q, secured to the stem of the check-valve c, which stem projects through a suitable stuffing-box from the valve-casing C'. A rod d, actuated by a suitable cam or eccentric on the crank-shaft, has feathered thereon a sleeve g, provided at its lower end with a lever h, and said sleeve g revolves in a fixed sleeve g', having at its lower end a sector-plate g², provided on its under side with a suitable guide for the lever h and on its upper face with suitable indices for positioning said lever. To the rod d at a suitable point is secured a block n, whose upper

will always lie in line with the free end of lever f , whatever may be the position of the vertical face of the block relatively to said lever, and said rod carries a radial arm m above the block n . As shown in Fig. 1, the vertical face of block n , which faces the valve-controlling rod k , is undulating, so as to form upper and lower projections e and e' , respectively, and a corresponding depression between said projections and below the lower projection e' , the block being in fact and performing the function of a cam relatively to the rod k and of a lifter relatively to the lever f . A spring f' , connecting the free arm of lever f with one of the bearings k' , tends to draw said arm down to hold the exhaust-valve a to its seat, said valve opening inwardly.

20 The operation of the motor is as follows: The storage vessel C^2 for the starting fluid having been charged, say, with compressed air by means of a hand-pump and the stop-cock in pipe C , leading from said vessel, 25 opened, the crank-shaft of the engine is turned to move the piston to the limit of its up-stroke, the parts being in their respective positions shown in Fig. 1. Upon further rotation of the shaft the piston, as well as the 30 rod d , moves downwardly. The roller k^2 on rod k moving over projection e' on block n opens valve c through bell-crank lever p , admitting air under pressure into cylinder A above its piston. The latter is driven downwardly, while the rod d also continues its downward motion. As the piston is about to reach the limit of its downward motion the radial arm m on rod d impinges upon valve-stem a' and opens exhaust-valve a to exhaust the 40 spent air. Under the momentum of the crank-shaft the piston moves upward again, as does also the rod d and its radial arm m , thereby allowing exhaust-valve a to close. As said piston is about to reach the limit of 45 its upward motion the rod k is again acted upon by the projection e' on block n to open valve c , admitting a second charge of compressed air, driving the piston downward again, while the rod d is still moving upwardly.

50 As the piston is about to reach the limit of its second downward motion the upper face of cam-block n impinges upon the free arm of lever f , lifting it against the stress of its spring f' and opening the exhaust-valve a . The piston moves upward again and as it begins its downstroke the rod d also moves down, thereby releasing valve-lever f , while the projection e' acts upon rod k to again open the valve c , so that the exhaust-valve a 60 will be opened by the action of the radial arm m and the rod k alternately, according as rod d moves downwardly or upwardly, the motor working as a two-cycle motor. As soon as the motor has acquired sufficient speed to 65 enable the piston to compress a charge of explosive gas the lever h is shifted from the position 1 to the position 2, Fig. 2, thereby

turning the rod d and block n , so as to move the cam face thereof out of reach of valve-controlling rod k and the arm m out of reach of valve-spindle a' , while the upper face of block n remains in line with the free arm of lever f . The motor is now working as a four-cycle motor. On the downstroke of the piston a charge of an explosive is drawn in through valve b^2 , which opens inwardly, said charge being compressed on the upstroke of the piston and ignited, the piston is driven down, and as it is about to reach the limit of its motion in that direction and while the rod d is still moving upward the valve a is opened through the lever f , after which the piston again moves down under momentum to draw in a charge of explosive gas, and so on. At every explosion of a charge a portion of the waste gases are forced through valve-casing C' and pipe C to the storage-cylinder, the load on the valve c in said casing—i. e., the power exerted by the spring c' to hold said valve to its seat—being so regulated as to resist the compressing pressure, but yield to the explosive pressure. In this manner the fluid under pressure necessary to the starting of the engine is automatically stored at the expense of but a comparatively small portion of the power developed.

It is obvious that instead of connecting the valve-casing C' directly with the power-cylinder it may be connected with pipe b' , and it is further obvious that instead of a hydrocarbon vapor and air other explosive gaseous compounds may be used.

Having thus described my invention, what I claim as new therein, and desire to secure by Letters Patent, is—

1. In a hydrocarbon or like motive-fluid engine, the combination with the cylinder, its explosive-fluid inlet, a valve organized to control gas under pressure, devices to actuate the same, and an exhaust-valve in the end of the cylinder; of a rod revoluble on its axis, a tappet thereon arranged to strike the exhaust-valve, a lever also arranged to operate the exhaust-valve, a cam on said rod arranged to operate the devices to actuate the valve to control gas under pressure and the lever, and means for rotating the rod to cause the said cam and tappet to run idle, substantially as and for the purpose set forth.

2. In a hydrocarbon or like motive-fluid engine, the combination with the exhaust-valve stem and its operating-rod d having endwise and rotary motion in its bearings, the radial arm m and the cam-faced block n on said rod; of the lever f connected with the aforesaid valve-stem and extending into the path of said cam-faced block and a lever h for turning the rod in its bearings, substantially as and for the purpose set forth.

3. In a hydrocarbon or like motive-fluid engine, the combination with the valve-stems a' and q , the operating-rod d having endwise and rotary motion in its bearings and carrying the radial arm m and cam-faced block n ,

adapted to actuate the aforesaid lever *f*, and the lever *h* for turning said rod in its bearings; of the lever *f* connected with the valve-stem *a'*, the spring-controlled bell-crank lever *p* having one of its arms connected with the valve-stem *q*, and the rod *k* having bearing on the other arm of said bell-crank lever, said lever *f* and rod *k* extending into the path of the aforesaid cam-faced block, substantially as and for the purpose set forth.

4. In a hydrocarbon or like motive-fluid motor, the combination with the power-cylinder having two passages leading from the combustion-chamber of said cylinder, a valve in each of said passages opening respectively toward and from said chamber, the bell-crank lever *p* one arm of which is connected

with the stem of the valve-opening from said combustion-chamber, the actuating-rod *k* connected with the other arm of said lever, 20 the exhaust-valve *a*, and the lever *f* connected with the stem of said valve; of the rod *d* carrying the radial arm *m* and the cam-faced block *n*, adapted to actuate the aforesaid rod *k* and lever *f*, and means for imparting a partial rotation to said rod in opposite directions, substantially as and for the purpose set forth.

In testimony whereof I affix my signature in presence of two witnesses.

HENRIK AUGUST BERTHEAU.
